CLAIM

The ornamental design for an intelligence enhancing toy, as shown and described.

DESCRIPTION

FIG. 1 is a top right perspective view of an intelligence enhancing toy showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view showing the design in its expanded configuration.

The broken lines are included for the purpose of illustrating portions of the intelligence enhancing toy that form no part of the claimed design.
